UNITED STATES PATENT OFFICE.

GEORGE CURCOUTIS, OF MONROVIA, CALIFORNIA.

THREE-IN-ONE VALVE.

Application filed February 2, 1923. Serial No. 616,578.

To all whom it may concern:

Be it known that I, GEORGE CURCOUTIS, a citizen of Greece, residing at Monrovia, in the county of Los Angeles and State of California, have invented new and useful Improvements in Three-In-One Valves, of which the following is a specification.

This invention relates to valves and more particularly to a three-in-one or mixing valve.

It is an object of the present invention to provide a simple, practicable, substantial and easily operative valve including means whereby either hot or cold water, or a mixture of the same may be dispensed.

Another object is to provide a valve having self-draining means to prevent undesirable leakage of the parts at their operating joints exterior to the valve.

Another object is to provide an index means for facilitating the adjustment of the valve members, and a further object is to provide a lock for fastening in open position the self-closing valve parts.

Other objects and advantages will be made manifest in the following specification of an embodiment of the invention illustrated in the accompanying drawings, wherein—

Figure 1 is a side elevation of the improved valve.

Fig. 2 is a top plan of the same.

Fig. 3 is a front elevation.

Fig. 4 is a central longitudinal section through the valve.

Fig. 5 is a section on line 5—5 of Fig. 4 showing the valve latching device.

Fig. 6 is a section on line 6—6 of Fig. 4.

Fig. 7 is a section on line 7—7 of Fig. 4.

Fig. 8 is a sectional detail on the lines 8—8 of Figs. 4 and 7.

The valve of the present invention consists of a suitably shaped shell or body 2 having a forwardly projecting discharge spout 3, the duct 3^a of which communicates with the lower interior portion of the shell, and in which portion is arranged a rotative core 4 which may be inserted upwardly through the bottom of the shell and retained as by a bottom closure 5 which may be screwed into place.

The shell 2 is provided with an upper chamber in which is mounted a spring 6 normally bearing down on a washer 7 having radial lugs 8 running in parallel channels 9 provided in the upper side walls of

the shell body, these side walls terminating in shoulders 10 adjacent the upper end of the core 4.

This core is provided with a plurality of apertures 12 and 13, Fig. 7, which are adapted to be selectively moved into register with the adjacent ends of the inlet ports through the nipples 14, so that hot or cold water, or a mixture, may be discharged from the valve. Hot and cold water are admitted as by means of a hot water pipe H and a cold water pipe C which are connected to nipples 14 provided on the sides of the shell 2 and which have passages in a higher plane than the pocket 4^a in the valve core 4 which is rotatively mounted, so that these ports can be shifted so that only hot water will be discharged through the spout or only cold water will be discharged, or a mixture of the same, as will be the case when the valve core 4 is positioned as shown in Fig. 7.

Suitable operating means are provided for rotating the valve core 4, and such means is shown as including a radially extending handle 15 which is pivotally connected at 16 to the upwardly extending stem 17 of a plug 18 which is adapted to move telescopically in a pocket 4^a in the top of the core 4. The pocket 4^a communicates with the spout 3. The plug 18 opens and closes the ports 12 and 13. The handle is adapted to be rotated and thereby to rotate the stem 17 and the plug 18 which is of noncircular cross section, or otherwise is nonrotatively attached to the core 4 so that the latter can be turned to the desired position by the handle; the position desired being indicated by index means shown as including suitable words or letters 19 provided on the upper end of the valve shell and contiguous to the pivoted end of the handle 15 which bears a pointer or indicating mark 20. When the plug 18 is raised and properly turned the water will pass through the ports 12 and 13 to the pocket 4^a and then to the spout 3.

The handle 15 having been positioned so as to register the ports 12 and 13 to accomplish the discharge of hot and cold water, or a mixture, it is then pressed downwardly so as to rock on the upper end of the shell 2 as a fulcrum and thus lift the stem 17 and the plug 18 a sufficient degree to open communication between the ports 12 and 13 and the pocket 4^a. If the plug ports have been

turned out of register with a hot and cold inlet, it will be clear that the covered hot or cold inlet will prevent the inflow of water while the uncovered hot or cold inlet registering with a port in the core 4 will permit the flow of water into the pocket 4^a and from this outwardly through the duct of the spout 3.

The plug 18 is automatically restored to its closing position by the downward pressure of the spring 6 acting on the nonrotative washer 7 which is supported on the rotative plug 18 and, therefore, the flow of water will be cut off as soon as pressure is relieved from the handle 15 by the downward movement of the plug 18 into a pocket 4^a.

It is desirable to provide means for fastening the valve elements, if desired, in open position so as to permit the flow of water for a desired length of time without requiring the holding down of the lever 15. To that end a sliding bolt or latch 22 is mounted in the handle 15 which is provided with a lateral pocket 23 in which is exposed a button 24 on the adjacent end of the latch 22. The opposite end of the latch is shown as slotted at 25 to pass around the stem 17 and passes outwardly so as to be shifted into upper and lower grooves 26 provided in an upwardly projecting wall 27 on the shell 2. When the latch 22 is fully withdrawn and the handle is in full closing position, the latch clears or rests below the lower slot 26 and flow is entirely cut off. Assuming a small flow is desired, the handle is tilted slightly to bring the latch into register with the lower slot 26 and the latch is then shifted in the handle to engage in this slot. If a larger flow is desired, the handle is tilted further and the latch is engaged in the upper slot 26. A still larger flow is obtained by tilting the handle down to such an angle as to bring the latch over the top of the wall 27 when the latch is again shifted to bear on the top end of the wall, thus holding the valve in full open position.

The latch 22 is shown as frictionally engaged by a spring finger 30 operating to hold the latch in its different positions.

To prevent drain through the top operating joints in the shell, the spout 3 is provided with a drain passage 3^a inclined upwardly and communicating with the spring chamber of the shell so that water passing upwardly into this chamber will be free to pass or drain out through the spout 3.

It will be seen that the turning of the handle 15 will be limited in its lateral extremes by engagement with the contiguous ends of the wall or flange 26 when the valve is fully open to serve either hot or cold water.

Further embodiments, modifications and variations may be resorted to within the spirit of the invention as here claimed.

What is claimed is:

1. A three-in-one valve comprising a shell having a discharge spout communicating with the interior of the valve, a rotary core mounted in the valve and having a plurality of ports in a plane above the spout duct, hot and cold water inlets in the plane of the ports so as to be registered therewith, and means for turning the core into register selectively with the inlets and providing for communication between the inlets and the discharge duct, the core having a pocket with which the ports communicate and said means including a plug fitting the pocket nonrotatively so as to rotate the core and movable in the pocket to uncover and cover the ports. 70 75 80

2. A three-in-one valve comprising a shell having a discharge spout communicating with the interior of the valve, a rotary core mounted in the valve and having a plurality of ports in a plane above the spout duct, hot and cold water inlets in the plane of the ports so as to be registered therewith, means for turning the core into register selectively with the inlets and providing for communication between the inlets and the discharge ducts, the core having a pocket with which the ports communicate and said means including a plug fitting the pocket nonrotatively so as to rotate the core and movable in the pocket to uncover and cover the ports, and a handle pivotally connected to said means for raising and lowering the plug and for rotating the plug and the core. 90 95 100

3. A three-in-one valve comprising a shell having a discharge spout communicating with the interior of a valve, a rotary core mounted in the valve and having a plurality of ports in a plane above the spout duct, hot and cold water inlets in the plane of the ports so as to be registered therewith, means for turning the core into register selectively with the inlets and providing for communication between the inlets and the discharge duct, means for automatically closing the ports of the core, and means to prevent automatic closure and for fastening the core operating means in selective positions to maintain a constant flow and means for draining leakage from the chamber of the shell and discharge the same outwardly through the spout. 105 110 115

4. A three-in-one valve comprising a shell having a discharge spout communicating with the interior of a valve, a rotary core mounted in the valve and having a plurality of ports in a plane above the spout duct, hot and cold water inlets in the plane of the ports so as to be registered therewith, means for turning the core into register selectively with the inlets and providing for communication between the inlets and the discharge duct, means for automatically closing the ports of the core, and means to prevent automatic closure and for fastening the core op- 120 125 130

erating means in selective positions to maintain a constant flow, said last named means operative to maintain discharge of different quantities according to adjustment and means for draining leakage from the chamber of the shell and discharge the same outwardly through the spout.

5. A three-in-one valve comprising a shell having a discharge spout communicating with the interior of a valve, a rotary core mounted in the valve and having a plurality of ports in a plane above the spout duct, hot and cold water inlets in the plane of the ports so as to be registered therewith, means 10 for turning the core into register selectively with the inlets and providing for communication between the inlets and the discharge duct, means for automatically closing the ports of the core, and means to prevent automatic closure and for fastening the core operating means in selective positions to maintain a constant flow, said last named means operative to maintain discharge of different quantities according to adjustment, and 15 which include an operating lever provided with a lever controlling latch and means for draining leakage from the chamber of the shell and discharge the same outwardly through the spout.

20 6. In a three-in-one valve, a shell having a discharge spout, a plug rotatively mounted in the shell and having a pocket to register with the spout duct and having a set of radial ports above the pocket, an operating 25 handle connected to a stem having a plug slidably but nonrotatively mounted in said pocket and whereby the core may be turned and the ports concurrently uncovered so as to provide for a discharge from inlets of the shell.

30 7. In a three-in-one valve, a shell having a discharge spout, a plug rotatively mounted in the shell and having a pocket to register with the spout duct and having a set of radial ports above the pocket, an operating 35 handle connected to a stem having a plug

slidably but nonrotatively mounted in said pocket and whereby the core may be turned and the ports concurrently uncovered so as to provide for a discharge from inlets of the 40 shell, and means for automatically moving the plug to a closing position.

8. A three-in-one valve comprising a shell having a discharge spout communicating with the interior of the valve, a rotary core 45 mounted in the valve and having a plurality of ports in a plane above the spout duct, hot and cold water inlets in the plane of the ports so as to be registered therewith, means for turning the core into register selectively 50 with the inlets and providing for communication between the inlets and the discharge duct, the core having a pocket with which the ports communicate and said means including a plug fitting the pocket nonrotatively so as to rotate the core and movable in the pocket to uncover and cover the ports, and means for draining leakage from the chamber of the shell and discharge the same 55 outwardly through the spout.

9. A valve comprising a shell having a discharge spout communicating with the interior of the shell, a rotary core mounted in the shell and having a plurality of ports and a pocket below the ports, hot and cold inlets 60 in the plane of the ports so as to be registered therewith, a plug mounted in the chamber and engaging said core so as to rotate the latter, a washer seated on said plug and having radial lugs sliding in the wall of the chamber and being prevented from rotation with said plug, and a spring confined 65 in said chamber and bearing upon said washer to force the plug down, said washer operating to prevent the rotation of the spring with rotation of the plug; said plug being operative to uncover the said ports and permit discharge through the core to the spout.

In testimony whereof I have signed my 70 name to this specification.

GEORGE CURCOUTIS.
